UNITED STATES PATENT OFFICE.

ADOLPH F. EUCHENHOFER, OF DAYTON, OHIO, ASSIGNOR TO THE STANDARD REGISTER COMPANY, OF DAYTON, OHIO, A CORPORATION OF OHIO.

AUTOGRAPHIC REGISTER.

1,221,521.

Specification of Letters Patent.

Patented Apr. 3, 1917.

Application filed July 6, 1915. Serial No. 38,059.

To all whom it may concern:

Be it known that I, ADOLPH F. EUCHENHOFER, a citizen of the United States, and a resident of the city of Dayton, in the county of Montgomery and State of Ohio, have invented certain new and useful Improvements in Autographic Registers, of which the following is a full, clear, and exact description, reference being had to the accompanying drawings, forming part of this specification.

My invention relates to autographic registers adapted to make two detachable registries and a record copy thereof, and my various improvements are shown as applied to the sprocket feed, perforated paper type of register. The register shown is furthermore provided with a special casing for attachment to a wall instead of standing on a desk or table as is the most familiar practice.

It is the object of my invention to provide a register of the recording type in which the secret record roll is readily accessible to the operator so that upon unlocking a special door the record strip may be drawn out without disturbing any of the other parts of the machine. It is further one of the objects to provide in connection with said door a simple and easy means available from the opening of the door for unlatching the other parts of the machine, and releasing the locking means for holding the spindles of the various feed rolls of the register. It is also the object of this invention to provide a means for holding the roll of carbon paper used in making the duplicate copies which is simple and inexpensive. And generally it is my object to provide a series of locks and friction releasing devices in connection with my novel door. Another object of the invention is to provide a special shaped curved back plate to engage and turn upwardly the duplicate slips as they are fed from the machine, this latter device being particularly useful in connection with registers of the type that are to be attached to a wall.

These objects and various other advantages as will be noted, I accomplish by that certain construction and arrangement of

parts to be hereinafter more specifically pointed out and claimed.

In the drawings,

Figure 1 is a side elevation of the machine taken from the right hand side.

Fig. 2 is a diagrammatic view showing the arrangement of the films or strips of paper used in the machine.

Fig. 3 is a central vertical section of the machine looking toward the right hand side thereof.

Fig. 4 is a perspective view of the special door.

Fig. 5 is a top plan view of the machine with parts broken away and with the lid removed and the door and secret record receiving roll sectioned.

Fig. 6 is a front elevation of the machine with the front wall thereof removed and sectioned at the right hand side to show the structure of the common locking plate for all paper roll shafts.

The machine has a casing, having the rear wall 1, side walls 2 and 3, and front wall 4. The rear wall is mounted on the wall of a booth or the like, by means of screws 5, 5, and the front wall is hinged at 6 to the base 7 of the casing, and has a spring latch 8 which engages over a pin 9 on the side wall 2. The front wall is held from falling too far open by a chain 10.

One of the side walls is provided with three diagonal slots 11 and the other side with corresponding holes in which to mount the three paper guide rollers 12, 12; and resting on the lugs 13, 13 along the inside at the top of the side walls is the tablet plate 14, which has depending pins 15 engaging between the central lugs. 90

The lid or top 16 of the machine is mounted on arms 17, 17, which are pivotally secured in the upwardly extending rear top portion 18 of the two sides. This lid carries in a semicylindrical casing 19 at its rear end in which is slidably mounted the spring-pressed friction roller 20 of usual design. Journaled in the side walls in a position beneath this friction roller is the toothed feed roller 21, having a series of teeth at each end to engage in suitable perforations in the webs of paper A, B and C, and 100

feed the paper over the tablet plate 14, as the roll is revolved. The feed roll is operated by a hand wheel 22, mounted direct on the shaft of the roll, the said wheel having a spring stop 23 which engages a stud 24 on the inner surface of the wheel. The stop is depressed each time the machine is operated by the thumb of the operator, it being located so as to permit of this.

10 The shaft of the feed roll has frictionally mounted at its other end, as described in said application, a gear 25 which meshes with a gear 26 mounted on the side wall 3. This gear 26 serves to operate the roll for receiving the record strip as will be described.

15 A spring finger 27 mounted at the rear of the side wall 2 is positioned so as to engage under the corner of the casing 19 on the lid portion, to hold it up when it is desired to get at the interior of the machine. The lid has a depending flange 28 at its forward end which is adapted to engage behind the outwardly and upwardly turned upper end 29 of the front wall. This device forms a lock for the lid or top, inasmuch as the top may be closed down and the front wall closed up over the said flange, thereby holding the top. The latch 8 thus serves as a locking means 30 for the entire machine.

20 Cut in the middle upper portion of the side wall 2 is a door opening 30 (Fig. 3) in which fits a door 31. The door has ears 32, 33 at its rear side to engage around the rear wall of the door opening, a ledge 34 to seat on the lower edge of the opening and a lock 35 having a bolt 36 which engages within the front wall of the opening. This door may thus be locked in place by means of the lock, 25 or the bolt may be withdrawn and the door lifted entirely out of the opening. In order to reach the latch 8, as well as to reach other releasing means as will be described, it is necessary first to take out the door as described, as this latch is positioned so as to be within reach of the operator through said door opening.

25 The three paper rolls 37, 38 for the two check strips and 39 for the record strip are mounted on spindles 40. These spindles have heads 41 for the use of the operator, and pass through proper apertures in each of the side walls so that the operator may pull out the spindles for renewing the paper rolls thereon. The spindles have peripheral grooves 42 in which are adapted to engage the arms 43 of a three-armed plate 44. This plate is slidably mounted on pins 45 which engage slots 46 in the plate, and is positioned so that its upper edge lies just beneath the door opening above described; and the plate is normally held in a position in engagement with the grooves in the paper roll spindles by means of a spring 47. To release the 60 spindles of the three rolls, it is necessary to

remove the door and lift up the plate 44, when the spindles may be withdrawn, for mounting a new roll of paper or the like by pulling on the heads 41, which lie outside of the machine.

70 As in the application above referred to, the two check strips A and B pass up and around the rollers 12, over the tablet plate, and thence to the feed roll where the teeth thereon engage proper perforations in the edges of the paper. The record strip C takes a like path, but as in said application, does not engage the teeth on the feed roll. It passes over the feed roll between the toothed portion thereof and is guided downwardly by a curved plate 48, where it passes between the feed roll and a further friction roll 49. The roll 49 has a pin and slot mounting in the side walls of the machine at 50, and is pressed upwardly into contact with the feed roll by a spring 51, as in said application. The storage roll 39 for the record paper is held under friction by a spring plate 52 which bears on its upper surface and is mounted on a shaft 53 extending across between the sides of the machine at the rear, and held by a spring 53^a, which connects with an arm 53^b on said shaft.

80 Means are provided for releasing simultaneously the three tension devices for the record strip, to wit: the friction rolls 20 and 49 and the friction plate 52.

85 Mounted pivotally on a stud 54 on the side wall 2 of the machine is a lever 55, having an arm 56 which bears against the end of a lever 58 pivoted at 59 to the side of the machine. When the lever 55 is depressed, the lever 58 will swing into contact with the arm 57 on the shaft 53 thereby rocking the friction plate 52 upwardly against its spring tension. The lever 58 has at its upper end a cam arm 60 which extends out over the friction roll 49 and a cam arm 61 which extends up to a position under the roll 20. When the lever 55, which is also located at the door opening referred to, is depressed, the friction plate 52 will be raised, the roll 49 pushed down and the roll 20 pushed up, thereby releasing all tension on the record strip. Owing to the cam surface of the end of the lever 58, when the lever 55 is depressed, it will stay down, and it will be possible to draw through the machine as much of the record strip as is desired, without keeping the finger on the said lever 55.

90 When this lever is in depressed position, it is impossible to replace the door because the lower of the two ears, *i. e.* the ear 33, on the door will strike the end of the lever owing to its position, thereby insuring that the proper friction will be thrown into operative position whenever the door is closed and locked.

95 The receiving roll for the record strip comprises a wooden spool 62 (Fig. 5) hav-

ing a metallic core 63, on which is mounted at the inner end the gear 63^a. A spindle 64 fixedly mounted in the side wall 3 of the machine and extending across to a point 5 where it will abut against the door when it is in closed position serves as a mounting for the metallic core, and the roll is to be slid over the spindle in mounting or removing it. The spindle is supported at one end 10 only and is rigid and non-removable. In mounting it, the gear 63^a is placed in mesh with the gear 26 which as before stated is in frictional operative connection with the feed roll 21, and the revolving of the feed 15 roll will cause the record receiving roll to rotate also. A pin 65 having a bent end 66 which is inserted in a hole in the wooden spool serves to take the initial hold on the record strip. The door 31 when it is in 20 closed position serves to hold the receiving roll in place.

It is thus obvious that the operator is enabled to close and lock the machine by means of the door, so that the hinged portions can 25 not be unlatched, the paper roll spindles may not be withdrawn, and the record roll friction 30 cannot be tampered with.

In placing the receiving roll for the record strip opposite the door opening a distinct 35 advantage is gained. The operator upon unlocking and removing the door has the said roll with the strip of paper containing the record directly in front of him. He may then release the friction on the strip 40 and roll as much as he desires onto the spool, by sliding the gear on the said spool just out of mesh with its driving gears; then taking a pair of scissors he may cut off the strip and draw out the roll with the complete 45 record of all transactions. These operations can be performed without in any way affecting the check strips because they are held in place by the engagement of their perforations with the teeth on the feed roll.

50 The strip may then be unwound from the roll to be filed with the business records, and the roll pushed back into place. The record strip is then drawn out so as to leave an end for securing it to the roll, and this strip secured to the roll by means of the pin already 55 described.

An upwardly curved plate 70 is provided, having end flanges 71, 71, (Fig. 3) for securing it to the upwardly extending portions 55 18 at the rear of the side walls, screws 72 being employed for this purpose. The plate when mounted lies just to the rear of the feed roll, and has slots 73 to clear the toothed 60 portions thereof and tongues 74, which lie just beyond the ends of the roll proper (Fig. 5). As the feed roll is rotated, and the check strips are drawn over the roll they will be engaged by the curved plate and turned upwardly so that they can be easily seized by 65 the operator for the purpose of tearing them

off. The cutting edge 75 for tearing is formed on the rear edge of the casing 19 for the upper friction roll 20. It is readily to be seen that the upward delivery of the duplicate checks is especially advantageous in 70 a machine that is to be mounted on a wall, but it is also of considerable advantage in doing away with the chance of the under strip being carried along with the record strip resulting in a clogging of the record 75 feeding mechanism.

A simple and inexpensive method for mounting the roll of carbon paper is provided. The trough 76 for the paper is mounted on the side wall 3 of the machine, and the lid of the machine is extended out at the side, as is customary, to cover over the trough when the machine is closed. A slot 77 is cut at the forward end of the trough and a proper aperture 80 is provided at the rear end thereof to receive the end of a spindle 78. The spindle has loosely mounted on it a spool 79 which holds the roll of carbon paper. A laterally extending pin 80 on the spindle forms 85 the stop for a spring 81 mounted on said spindle, and this spring bears against a disk 82 that is slidably mounted on the spindle and bears against the end of the spool. In mounting the carbon roll it is wound on the 90 spool and the spool placed over the rod. The disk is pulled back against the pressure of the spring so as to allow the rear end of the spindle to extend well out of the spool, and this end inserted through the aperture 95 100 in rear of the trough. The forward end of the spindle is then dropped into the slot 77 in the trough and the pin 80 turned so as to engage behind a stud 83 at the forward end of the trough. The paper is then ready to 105 be drawn out in sufficient length to reach across the tablet top of the machine, and the friction of the disk 82 will hold it taut once it is in place. At the other side of the machine, the customary arm 84 is provided, 110 and adapted to swing downwardly to engage over the ends of the films of carbon paper, and clamp them in place, the arm coming into engagement in depressed position with a finger 85 on the side of the machine, as is also customary. 115

By specific description of parts without reference to possible equivalent structures, it has not been intended to limit the claims that follow to specific structure where they 120 are not particularly worded to include it.

Having thus described my invention, what I claim as new and desire to secure by Letters Patent, is:—

1. In an autographic register, the combination of a casing for the machine, a feed roll for duplicate check strips, a gear actuated thereby, a fixed transverse spindle for removably mounting a record strip receiving roll, a gear on said roll to mesh with the 125 130

gear first mentioned, an aperture in the casing, adjacent the end of the receiving roll and means for closing the said aperture, said parts being so proportioned that the 5 aperture closing means lies against the transverse spindle, to hold the receiving roll in place.

2. In an autographic register, the combination of a casing for the machine, a feed 10 roll, a gear connected thereto, a transverse spindle for removably mounting a record strip receiving roll, a gear on said roll to mesh with the gear first mentioned, an aperture in the casing, adjacent the end of the 15 feed roll, a tensioning device for the feed roll, means for releasing the tensioning device located adjacent the aperture, the parts being so positioned that the aperture closing means lies against the transverse 20 spindle, to hold the receiving roll in place.

3. In an autographic register, the combination of a casing therefor paper therein and paper feeding mechanism therein, tension devices adapted to hold said paper, a 25 lever for releasing said tension, an aperture in the casing, said lever located at one side of the aperture, means for closing said aperture, and means on said closing means for contacting with the lever in tension releasing 30 position to prevent closure of said means with the lever at such position.

4. In an autographic register, the combination of a casing for the machine, a driving mechanism, a record receiving roll, an aperture 35 in the casing, a closure for the aperture, means for removably mounting the roll

in the casing with its one end abutting the closure in the aperture, and means for operatively connecting the roll with the driving mechanism, for the purpose described. 40

5. In an autographic register, in combination with a casing for the machine, driving mechanism, a record receiving roll, an aperture in the casing, a closure for the aperture, a spindle in the casing on the opposite side 45 from said aperture and extending across to the aperture, means for slidably mounting the roll on the spindle with its end abutting the closure and means for operatively connecting the roll with the driving mechanism, 50 for the purpose described.

6. In an autographic register, the combination of a casing for the machine, storage rolls for paper removably mounted in the casing, slots in the rolls, and a plate mounted slidably on the casing and having arms 55 to simultaneously engage all of the slots in the rolls.

7. In an autographic register, having a casing provided with an aperture, storage 60 rolls for paper, feeding elements with tensioning members bearing thereon, a tablet top over which the papers are drawn, means for locking down the tablet top, means for locking the storage rolls against removal, 65 and means for releasing the tensioning members, all of said locking and releasing means positioned adjacent the aperture in the casing, and a closure for said aperture adapted to be locked in place from without 70 the register, for the purpose described.

ADOLPH F. EUCHENHOFER.
